MULTIPLE CONTROL APPARATUS

Heward A. Thompson, Edgewood, Pa., assignor to
 The Union Switch & Signal Company, Swiss-
 vale, Pa., a corporation of Pennsylvania

Application January 2, 1930, Serial No. 417,973
 Renewed May 7, 1935

18 Claims. (Cl. 246—134)

My invention relates to multiple control apparatus, and is particularly adapted for, though not limited to, the control of the railway track switches and signals in a railway switching or 5 interlocking layout.

One feature of my invention is the provision of means for controlling the devices in each of various partly inter-inclusive groups by a single movable contact member in cooperation with a 10 plurality of fixed contact members. Another feature of my invention is the provision of interlocking control for various groups of devices by means of sliding contact members operated along intersecting guides.

15 I will describe one form of apparatus embodying my invention, and will then point out the novel features thereof in claims.

The accompanying drawings, Figs. 1 to 17, inclusive, some of which are diagrammatic, illustrate one form of apparatus embodying my invention. Fig. 1 is a view illustrating a control panel for a railway switch and signal layout which is shown diagrammatically in Fig. 8. Figs. 2 to 7, inclusive, are views showing portions of 25 the apparatus of Fig. 1. Figs. 8 to 16, inclusive, are diagrammatic views showing means controlled by the apparatus of Fig. 1 for controlling the switches and signals of Fig. 8. Fig. 17 is a diagrammatic view showing indication means 30 controlled by the signals of Fig. 8 in association with parts of the apparatus shown in Fig. 12.

Similar reference characters refer to similar parts in each of the views.

Reference characters in Figs. 8, 10, 11, and 35 13 to 16, inclusive, refer to parts which are similar to parts designated by similar reference characters in Figs. 1, and 6 to 11, inclusive, of my application for Letters Patent of the United States, Serial No. 416,061, filed Dec. 23, 1929, for Multiple 40 control apparatus.

Referring to Fig. 8, a stretch of double track railway is here shown, tracks *aa* and *bb* of which are interconnected through crossover *ee* to which they are respectively joined by switches *H*² and 45 *H*^{2a} and are likewise interconnected by cross-over *ff* to which they are respectively joined by switches *H*³ and *H*^{3a}. Tracks *aa* and *bb* are also respectively joined to passing sidings *cc* and *dd* by switches *H*⁴ and *H*¹.

50 The reference character *S*, with distinguishing exponents, designates signals which are placed adjacent the points *A*, *B*, *C*, *D*, *E* and *F*, respectively, and which, as here shown, are of the semaphore type. Signals *S*^{1a}, *S*^{1b} and *S*^{1c} are mounted 55 on a common mast *549*, and signals *S*^{4a}, *S*^{4b} and

S^{4c} are mounted on a common mast *550*. Signals *S*^{1a}, *S*^{1b}, *S*^{1c}, *S*² and *S*³ govern eastbound traffic moves, that is, moves which are made over the stretch of track from left to right as shown in the drawings, and signals *S*^{4a}, *S*^{4b}, *S*^{4c}, *S*⁵ and *S*⁶ 5 govern westbound traffic moves, that is, moves which are made over the stretch of track from right to left as shown in the drawings.

Between the group of eastbound signals and the group of westbound signals, eleven different routes 10 may be established according to the positions of the various switches. Over each of these routes, traffic can proceed in either direction, that is, from west to east or from east to west. The arrangements of the switches for these various 15 routes are as given in the following table:

Route 1.—A to E, switches *H*², *H*³, and *H*⁴ normal.

Route 2.—A to F, switches *H*² and *H*³ normal, and *H*⁴ reversed. 20

Route 3.—A to D, switches *H*² and *H*^{2a} reversed, and *H*^{3a} normal.

Route 4.—A to E, switches *H*², *H*^{2a}, *H*^{3a} and *H*³ reversed, and *H*⁴ normal.

Route 5.—A to F, switches *H*², *H*^{2a}, *H*^{3a}, *H*³, and *H*⁴ reversed. 25

Route 6.—B to D, switches *H*¹, *H*^{2a}, and *H*^{3a} normal.

Route 7.—B to E, switches *H*¹, *H*^{2a}, and *H*⁴ normal, and *H*^{3a} and *H*³ reversed. 30

Route 8.—B to F, switches *H*¹ and *H*^{2a} normal, and *H*^{3a}, *H*³ and *H*⁴ reversed.

Route 9.—C to D, switch *H*¹ reversed, and switches *H*^{2a} and *H*^{3a} normal.

Route 10.—C to E, switches *H*¹, *H*^{3a}, and *H*³ reversed, and *H*^{2a} and *H*⁴ normal. 35

Route 11.—C to F, switches *H*¹, *H*^{3a}, *H*³ and *H*⁴ reversed, and *H*^{2a} normal.

Referring now to Fig. 1, a control panel is here shown comprising an insulating plate *57* mounted on a second insulating plate *58*, a portion of which is shown in Figs. 2, 3, 6 and 7. Channels *66* are cut in plate *58* according to an arrangement which is similar to, and which constitutes a diagram of, the track layout shown in Fig. 8. The junctions of these channels *66* are designated by the reference character *H* with distinguishing exponents, as shown in Fig. 8 for the corresponding switches. 40

Diagrams of signals, designated by the reference character *S* with distinguishing exponents similarly to the corresponding diagrams shown in Fig. 8, may be painted or otherwise suitably applied on the surface of plate *57*. Slots *67* are cut in plate *57* according to an arrangement which is 45 50 55

similar to that of channels 66 in plate 58 except that slots 67 extend only from points adjacent the letters C, B and A to points adjacent the letters D, E and F, whereas channels 66 extend to the left of letters C, B and A and to the right of letters D, E and F. In Fig. 6, a section is shown through a channel 66 and the corresponding slot 67.

Fixed contact members, designated by the reference character z with distinguishing exponents, are mounted in the control panel. Each of these members comprises two elements p which are located opposite each other along one of the channels 66. Contact members z , acting in cooperation with movable contact members, control the switches and signals shown diagrammatically in Fig. 8.

The contact members for controlling the signals are distinguishable by exponents for the reference character z comprising the letter S with a number corresponding to the number in the exponent of the reference character for the corresponding signal. For example, contact member z^{s5} controls signal S^5 , and contact member z^{s4} controls signals S^{4a} , S^{4b} and S^{4c} .

Two members z are employed for controlling each single switch, and three members z are employed for controlling the pair of switches in each crossover. One of the members z for each single switch controls operations of the switch to its normal position, and is distinguishable by an exponent comprising the letter n and a number corresponding to the number in the exponent for the reference character for the corresponding switch. The second member z for each single switch control operations of the switch to its reverse position, and is distinguishable by an exponent comprising the letter r and the number in the exponent for the reference character for the corresponding switch. For example, the member z^{4r} controls operations of switch H^4 to its normal position, and the member z^{4n} controls operations of switch H^4 to its reverse position.

Each of two of the members z for each crossover controls operations of both switches in the crossover to their normal position. These members are distinguishable by an exponent comprising the letter n and the exponent for the reference character for each of the switches in the crossover, respectively. The third member z for each crossover controls operations of both switches in the crossover to their reverse position, and is distinguishable by an exponent comprising the letter r and the number in the exponents for the switches of the crossover.

Each element p of each member z , as shown in Figs. 5 and 5^a, comprises a terminal 62 to which a flat spring 63 is attached. In Fig. 7 is shown a section through elements p of member z^{3n} . Each element p , as here shown, is rigidly attached to plate 58 adjacent a channel 66 by means of nuts 64 and a washer 65.

Each movable contact member which cooperates with fixed contact members z for controlling the switches and signals comprises a flexible device, here shown as a chain, which slides in certain channels 66. The channels 66 serve as guides for the movement of the chains. Each of these chains consists of a plurality of main links 60, —see Figs. 1, 2, 3, 4 and 4^a,—and end links 60^a and 60^b connected together vertically with respect to the control panel by pins 61 so that the chain is flexible horizontally. A post 59 is rigidly fastened in end links 60^a of each chain. By means of this post, the chain is manually movable along

certain channels 66 according to the route which the operator desires to arrange. Each chain, when moved along corresponding channels 66, connects one element p of each member z adjacent these channels with the other element p of the same member z as the chain successively engages these members. The elements p of each member z remain thus connected with each other until the chain is returned to the normal position in which the post 59 is adjacent one of the letters A, B, C, D, E or F as shown in the drawings.

Push buttons for controlling the call-on indication of signals S^{1a} and S^{4c} are mounted in the control panel adjacent the corresponding signal diagrams, and are designated by the reference character K with an exponent comprising the reference character S and the exponent number of the corresponding signal.

Fig. 2 is a sectional view of a portion of the control panel and the chain shown to the left of letter A.

Fig. 3 is a view of the chain to the left of letter A and a portion of plate 58 with plate 57 removed.

Figs. 4 and 4^a comprise a plan and a side elevation view, respectively, of one of the links 60 of the control chains.

Fig. 6 is a sectional view of a portion of the control panel showing a channel 66 in plate 58 and the associated slot 67 in plate 57.

Referring again to Fig. 8, the reference characters 1 and 1^a designate the rails of track aa, and the reference characters 2 and 2^a designate the rails of track bb. These rails are divided by insulated joints 3 to form a plurality of track sections a—A, A—ii, ii—jj, jj—E, B—mm, mm—G, G—D, and D—d. Each of these track sections is supplied with current by a battery 4 connected across the rails adjacent one end of the section. A track relay, designated by the reference character T with a distinguishing exponent, is connected across the rails adjacent the opposite end of each track section.

Each track section in which a switch is located will be referred to hereinafter as a detector section. Track sections a—A and d—D in the rear of signals S^1 and S^4 , respectively, will be referred to as approach track sections.

Each switch H is operated by a motor which is controlled by pole-changing contacts of a polarized switch control relay m as already shown and described in my application for Letters Patent of the United States, Serial No. 416,061, filed Dec. 23, 1929, to which I have already referred in this present application. Polarized switch indication relays, designated by the reference character h with distinguishing exponents corresponding to the numbers in the exponents for the reference characters for the switches, are controlled by the switches as also already shown and described in my former patent application to which I have just referred.

For each switch indication relay h, there is a reverse indication relay designated by the reference character t with a distinguishing exponent and a normal indication relay designated by the reference character i with a distinguishing exponent. The controls for relays t and i are similar to those shown in my patent application, Serial No. 416,061, except that an additional contact is included in each circuit, as, for example, contact 558^{t4} in the circuit for relay t^{4a} and contact 557^{t4} in the circuit for relay i^{4a} .

Approach locking relays, designated by the reference characters P^{s1} and P^{s4} , are controlled ex-

- actly similarly to the relays designated by the same reference characters, respectively, in my former patent application, Serial No. 416,061. Stick locking relays Q^{S^2} , Q^{S^3} , Q^{S^5} and Q^{S^6} , and thermal relays N^{S^2} , N^{S^3} , N^{S^5} and N^{S^6} are also controlled exactly similarly to the relays designated by the same reference characters, respectively, in my former patent application referred to above. Relays X^{1a} , to X^{6a} , inclusive, which enter into the controls for relays P and Q in my present application, are, however, controlled in a different manner from relays X^1 to X^6 , inclusive, which enter into the controls for relays P and Q in my former patent application.
- 15 Track relays T^2 to T^7 , inclusive, slow-releasing relays I^2 to I^7 , inclusive, and repeater relays U^2 to U^7 , inclusive, are controlled exactly similarly to relays having corresponding reference characters, respectively, in my patent application, Serial No. 416,061. The control circuits for these relays are therefore omitted from the drawings in my present application.

In each of the drawings, the contacts operated by the various relays, or by time releases J, or by other control devices which will be hereinafter described, are identified by numbers, such numbers having distinguishing exponents when such contacts are not shown adjacent the respective relay, release, or other device by which the contacts are operated. The exponent for each of these contact numbers comprises the reference character and exponent of the respective relay, release, or other device. For example, the exponent U^5 for contact $39U^5$, shown in the circuit for relay Q^{S^2} in Fig. 8, comprises the reference character U and its exponent 5 for repeater relay U^5 which operates contact $39U^5$. Similarly, exponent m^4 for contact $14m^4$ in the control circuits for relay t^{1a} and t^{4a} comprises reference character m and its exponent 4 for a switch control relay m^4 which operates $14m^4$. Also exponent J^{S^1} for contact $515J^{S^1}$ in the circuits for signals S^1 , shown in Fig. 16, comprises reference character J and its exponent S^1 for a time release J^{S^1} which operates contact $515J^{S^1}$.

In Fig. 9, relays designated by the reference character n or r with distinguishing exponents are shown controlled by the fixed contact members z , for the normal and reverse control respectively, of the various switches, when the elements p of these contact members are bridged by a link 60 of one of the control chains shown in Figs. 1, 2 and 3.

Referring to Fig. 10, route locking relays, each of which is designated by the reference character V with a distinguishing exponent including the letter e , are controlled to prevent operation of the switches in each route when an approach or stick locking relay P or Q, respectively, for the eastbound direction of the corresponding route has been deenergized. Route locking relays, each of which is designated by the letter V with an exponent including the letter w , are similarly controlled to prevent operation of the switches in each route when an approach or stick locking relay P or Q, respectively, for the westbound direction of the corresponding route has been deenergized.

In Fig. 11 are shown the circuits for polarized switch control relays m controlled by normal and reverse switch control relays n and r , respectively, of Fig. 9. Control of relays m by either normal or reverse control relays n or r , respectively, is prevented when certain track repeater relays U or certain route locking relays V or certain ap-

proach or stick locking relays P or Q, respectively, are de-energized.

Fig. 12 shows relays designated by the reference character k with distinguishing exponents, each of which is controlled by a fixed contact member z for a signal when the elements p of such a contact member are bridged by a link 60 of one of the control chains. The exponents for the reference character k correspond with the numbers in the exponents for the reference characters for the associated signals, respectively.

Each relay k controls a route relay designated by the reference character Y with an exponent corresponding with that of the associated relay k . Each relay Y is also controlled by normal and reverse switch control relays n and r , respectively, for all the switches in each route with which the relay Y is associated. Each route relay Y is also controlled by a back contact of the route relay for movements in the opposite direction over the same route. In this way, protection is provided against trouble on account of a control chain contemporaneously closing contact members z for opposing signals.

Referring now to Fig. 13, route relays Y are here shown controlling signal control relays each of which is designated by the reference character X with an exponent which includes the exponent for the associated relay Y . Each relay X is also controlled by a normal or a reverse indication relay i or t , respectively, and by a normal or a reverse switch control relay n or r , respectively, for each switch in a route controlled by an associated signal, and hence all switches in a given route must be in the proper position and the relays n and r for the route must be energized before the relay X for that route can become energized. Each relay X is also controlled by a back contact of the relay X for the opposite traffic direction of the same route.

Signal stick relays are shown in Fig. 14. Each of these relays is designated by the letter L with an exponent to indicate the signals with which it is associated. Each of these stick relays is controlled by the approach locking relay P which is associated with the same signals, as well as by repeater relays U for all tracks over which the signals govern.

Fig. 15 shows the control circuits for signal call-on relays, each of which is designated by the reference character R with an exponent to indicate the signal with which it is associated. Each of these call-on relays is provided with a pickup circuit which is controlled by its call-on push button K , and is provided with a stick circuit which is controlled by the signal control relay X for the same signal.

In Fig. 16 are shown the local control circuits for the various signals controlled by signal relays X . Signals S^1 and S^4 are also controlled by normal or reverse indication relays for the switches in the routes governed by these signals.

In Fig. 17, an indication means shown as an electric lamp w is controlled by a relay v . Relay v is, in turn, controlled by contacts 93 of relays Y in association with contacts 93 , 94 and 95 which are operated by signals S . Each of the contacts 93 connects with a terminal e when its signal is indicating stop, and connects with a terminal f when its signal is indicating proceed. Each of the contacts 94 is closed when its signal is indicating stop, and each of the contacts 95 is closed when its signal is indicating proceed.

Having thus described, in general, the arrangement and location of the various parts comprising

ing my invention, I will now explain the operation of the apparatus.

- As shown in the drawings, all parts are in their normal condition, that is, each of the track sections shown in Fig. 8 is clear, each of the control chains of Fig. 1 is in its normal position, as shown, each switch H is in its normal position, and each of the signals S is indicating "stop". Since each of the track sections is clear, each of the relays T and U is energized, and each of the relays I is de-energized. With each of the switches in its normal position, each of the polarized indication relays h is energized in the normal direction.
- With signals S^1 indicating "stop" approach locking relay PS^1 is energized by its circuit passing from terminal x of a source of current not shown in the drawings, through contacts 21 , 22 and 23 operated by signals S^{1a} , S^{1b} and S^{1a} , respectively, contact 24 of relay T^1 in multiple with contact 55^1 of relay PS^1 , contact $27X^{1a}$, and the winding of relay PS^1 to terminal o of the same source of current. Approach locking relay PS^4 is energized by a circuit which is similar to that just traced for relay PS^1 .

With signal S^2 indicating "stop", stick locking relay QS^2 is energized by its circuit passing from terminal x , through contact 28 of signal S^2 , contact $29X^{2a}$, contact 33 of relay QS^2 , and the winding of relay QS^2 to terminal o . Stick locking relays QS^3 , QS^4 and QS^6 are energized by circuits which are similar, respectively, to the circuit just traced for relay QS^2 .

With all approach and stick locking relays P and Q energized, and with all track repeater relays U energized, all of the route locking relays V are energized as shown in Fig. 10. For example, relay V^{2ae} is energized by a pick-up circuit passing from terminal x , through contacts $559QS^3$, $560QS^2$, $561PS^1$, $563U^2$, $565U^5$, $566U^6$, and the winding of relay V^{2ae} to terminal o . A stick circuit for relay V^{2ae} is also closed, which is the same as the pick-up circuit just traced as far as contact $561PS^1$, and thence passing through contact 561 of relay V^{2ae} , and the winding of relay V^{2ae} to terminal o .

I will now assume that the operator in charge desires to arrange for a traffic movement over Route 1, from A to E. He, therefore, takes hold of the post 59 of the chain shown to the left of letter A in Fig. 1, and pulls it to the right, causing links 60 of the chain to bridge the elements p of contact members z^{81} , z^{2n} , z^{3n} , and z^{4n} , successively, in the order named.

When contact member z^{81} is closed by the bridging of its elements p by the chain, relay k^1 , shown in Fig. 12, becomes energized by its circuit passing from terminal x , through contact member z^{81} , and the winding of relay k^1 to terminal o .

Upon the closing of contact member z^{2n} , relay n^2 shown in Fig. 9, becomes energized by its circuit passing from terminal x , through contact member z^{2n} , and the winding of relay n^2 to terminal o . Relay n^2 , upon becoming energized, closes its front contact 590^{n2n} , causing relay m^2 , shown in Fig. 11, to be energized in the normal direction by its circuit passing from battery gg , through contacts 590^{n2} , $592V^{3w}$, $594V^{2aw}$, $595V^{2ae}$, $596PS^1$, $597U^2$, $598U^6$, and the winding of relay m^2 to terminal 441 which is common to batteries gg and hh , and thence back to battery gg . Since switches H^2 and H^{2a} are already in their normal position, no movement of these switches is pro-

duced by the energization of relay m^2 as just traced. Upon the closing of contacts z^{3n} and z^{4n} , relays n^3 and n^4 are energized similarly to relay n^2 as already described, and relays m^3 and m^4 are therefore energized in the normal direction by their circuits passing through front contacts 599^{n3} and 614^{n4} , which are similar to the circuit previously traced for relay m^2 .

When relays k^1 , n^2 , n^3 and n^4 are all energized, a circuit is completed for relay Y^1 , shown in Fig. 10, 12, passing from terminal x , through contacts 622^{ys} , 623^{n4} , 633^{n3} , 634^{n2} , 635 of relay k^1 , and the winding of relay Y^1 to terminal o . Relay Y^1 becoming thus energized, opens its contact 641^{Y1} , thus preventing the possibility of relay Y^5 becoming energized by its circuit through contact 649 of relay k^5 .

When relay Y^1 becomes energized, a circuit is completed for relay v passing from terminal x , through contact $93S^{1c}$, terminal e , contacts $94S^{1b}$ and $94S^{1a}$, front contact 96^{Y1} , and the winding of relay v to terminal o . Lamp w then becomes lighted by its circuit passing from terminal x , through contact 97 of relay v , and lamp w to terminal o .

When relay n^4 becomes energized, normal indication relay i^{4a} becomes energized by its circuit passing from battery 13 , through normal contact 14^{m4} , contact 557^{n4} , contacts 15 and 16 of relay h^4 , contact 17 of relay t^{4a} , and the winding of relay i^{4a} back to battery 13 . Relays i^{2a} and i^{3a} and energized by similar circuits when relays n^2 and n^3 become energized.

With relay Y^1 energized, a circuit is then completed for relay X^{1a} , shown in Fig. 13, passing from terminal x , through contact 676 of relay X^{5a} , back contact 677^{Y5} , contacts 678^{i4a} , 679^{i4} , 671^{i3a} , 670^{i3} , 669^{i2a} , 668^{n2} , front contact 663^{Y1} , and the winding of relay X^{1a} to terminal o .

Relay i^{2a} upon becoming energized causes relay L^{S1} to become energized by its circuit passing from terminal x , through contacts 43^{i2a} , 44^{U3} , 45^{U4} , 46^{U2} , $47PS^1$, and the winding of relay L^{S1} to terminal o . Relay L^{S1} upon becoming energized closes its stick circuit which includes its own contact 48 instead of contact $47PS^1$ in the pick-up circuit just traced.

Relay X^{1a} upon becoming energized completes an operating circuit for signal S^{1a} passing from terminal x , through contacts $514X^{1a}$, $515JS^1$, 516^{i2a} , $50^{517^{i4a}}$, 518^{LS1} , contact 519 operated by signal S^{1b} , and the mechanism of signal S^{1a} to terminal o . The arm of signal S^{1a} therefore moves to its "proceed" position, breaking, at its contact 23 , the pick-up and stick circuits already traced for relay PS^1 . Relay PS^1 is thereby de-energized, and hence opens its contact $561PS^1$ in the circuits already traced for relay V^{2ae} . Relay i^{2a} is now energized, however, and hence its contact 562^{i2a} is closed, forming a branch path around contact $561PS^1$ and hence relay V^{2ae} continued energized. Relay PS^1 upon becoming de-energized also opens its contact $571PS^1$ in the circuits for relay V^{3e} , and since relay t^{2a} is de-energized, relay V^{3e} now becomes de-energized. On account of relay PS^1 being de-energized, the circuit already traced for relay m^2 is open at contact $596PS^1$. The normal control circuits for relays m^3 and m^4 are open at contacts $602V^{3e}$ and $615V^{3e}$, respectively.

The arm of signal S^{1a} , upon leaving its stop position, also opens its contact $94S^{1a}$, causing relay v to be de-energized and so causing lamp w to be extinguished. The operator is thus informed that the switches in the route are in the 75

positions required for the route, and that the arm of signal S^{1a} has left its stop position.

An eastbound train approaching signal S^{1a} , after the route from A to E has been arranged as just described, de-energizes approach track relay T^1 which then opens its contact 24 in the pick-up circuit already traced for relay P^{S1} which, however, is already open at contact 23 of signal S^{1a} . When the train passes signal S^{1a} , entering section A—ii, relay T^2 and, in turn, relay U^2 becomes de-energized, and relay I^2 becomes energized. Relay U^2 , upon becoming de-energized, opens its contact 575 U^2 in a pick-up circuit for relay V^{3e} which, however, is already de-energized as previously described, and also opens its contact 597 U^2 in the circuit traced for relay m^2 . Relay U^2 , upon becoming de-energized, also opens its contact 46 U^2 in the circuit for relay L^{S1} , causing relay L^{S1} to become de-energized. Relay L^{S1} , upon becoming de-energized, opens its contact 518 L^{S1} in the circuit already traced for signal S^{1a} , and so causes the arm of signal S^{1a} to return to its stop position.

With the arm of signal S^{1a} again in its stop position, relay v is again energized by its circuit previously traced, causing lamp w to again become lighted. The operator is therefore informed that a train is passing signal S^{1a} .

If now the operator returns the control chain for the route from A to E to its normal position to the left of letter A of Fig. 1, he will de-energize relays n^4 , n^3 , n^2 and k^1 in the order just named. Relay Y^1 and, in turn, relay X^{1a} therefore become de-energized. Front contacts 599 n^2 , 599 n^3 and 614 n^4 are opened in the circuits for relays m^2 , m^3 and m^4 respectively, which, however, have already been broken by relays P^{S1} and V^{3e} as already described. With relay X^{1a} de-energized, and with the arm of signal S^{1a} now again in its "stop" position, and with relay U^2 de-energized, a second pick-up circuit is completed for relay P^{S1} passing from terminal x , through contacts 21, 22 and 23 of signals S^{1c} , S^{1b} and S^{1a} , respectively, contact 26 of relay U^2 , contact 27 X^{1a} , and the winding of relay P^{S1} to terminal o .

With relay Y^1 de-energized, front contact 96 Y^1 is open, and hence relay v is again de-energized and lamp w is therefore extinguished.

As long as the train remains in section A—ii, the pick-up circuit for relay V^{3e} continues open at contact 575 U^2 , and when the train has entered section ii—jj and has left section A—ii, relay V^{3e} , on account of contact 577 U^3 being open, remains de-energized although relay U^2 closes its contact 575 U^2 . When the train moves out of section ii—jj, relay U^3 again becomes energized and hence relay V^{3e} becomes energized by its pick-up circuit passing from terminal x , through contacts 571 P^{S1} , 573 V^{3e} , 575 U^2 , 577 U^3 , and the winding of relay V^{3e} to terminal o . Relay V^{3e} , upon becoming energized, completes its stick circuit which follows the path just traced as far as contact 573 V^{3e} , thence through contacts 578 of relay V^{3e} , and the winding of relay V^{3e} to terminal o . When the train leaves section jj—E, all parts of the apparatus will therefore again be in the normal condition.

If, after a route has been arranged for a move such as from A to E as previously described, a train has entered the route, causing lamp w to be lighted as already traced, and the operator then desires to provide a call-on signal indication to authorize a second train to enter the route while it is still occupied by the first train, he will, while

the chain is still bridging contact elements z^{S1} , z^{2n} , z^{3n} and z^{4n} , depress push button K^{S1} shown adjacent signal S^{1c} . With push button K^{S1} depressed, call-on relay R^{S1} , shown in Fig. 15, becomes energized by its circuit passing from terminal x , through contact 588 K^{S1} , and the winding of relay R^{S1} to terminal o . Relay R^{S1} , upon becoming energized, completes its stick circuit passing from terminal x , through contact 507 X^{1a} , contact 508 of relay R^{S1} , and the winding of relay R^{S1} to terminal o . Relay R^{S1} will therefore continue energized by its stick circuit as long as relay X^{1a} continues energized although the operator ceases to depress push button K^{S1} . With relay R^{S1} energized, a circuit is now completed for signal S^{1c} passing from terminal x , through contacts 514 X^{1a} , 515 S^{1c} , 515 S^{1a} , 517 S^{1a} , 536 R^{S1} , 528 of signal S^{1a} , 529 of signal S^{1b} , and the mechanism of signal S^{1c} to terminal o . The arm of signal S^{1c} thereupon moves to its "proceed" position, breaking at its contact 93 S^{1c} , 20 the circuit previously traced for relay v . Relay v then opens its contact 97, extinguishing lamp w .

Since the circuit just traced for signal S^{1c} does not include any traffic controlled relay contacts, the arm of signal S^{1c} will continue to indicate "proceed" until the operator returns the control chain toward its normal position.

When the operator is returning the control chain toward its normal position, relay Y^1 becomes de-energized as soon as relay n^4 opens its contact 623 n^4 . Relay Y^1 then completes, at its back contact 96 Y^1 , a second circuit for relay v , passing from terminal x , through contact 93 S^{1c} , terminal f , back contact 96 Y^1 and the winding of relay v to terminal o . Relay v then again closes its contact 97, causing lamp w to again become lighted.

When the operator is returning the control chain toward its normal position, relay X^{1a} also becomes de-energized as soon as relay n^4 opens its contact 679 n^4 , and hence relay X^{1a} opens its contact 514 X^{1a} , causing the arm of signal S^{1c} to return to its stop position before the operator has completed the return of the control chain to its normal position. When the arm of signal S^{1c} leaves its proceed position, contact 93 S^{1c} opens, causing relay v to again be de-energized and hence lamp w to become extinguished. The operator is thereby informed that the arm of signal S^{1c} has responded to his movement of the control chain. The arm of any of the other signals shown in Fig. 8 is similarly returned to its stop position when a corresponding control chain is returned toward its normal position.

I will now assume that with all parts of the apparatus again in the normal condition as previously described, the operator arranges Route 1 for a move from A to E and clears signal S^{1a} , as previously traced, by moving the control chain along the guides in the control panel corresponding with the route A to E. If, now, after an eastbound train enters section a—A, de-energizing relay T^1 , the operator should desire to send the train over some other route than Route 1, he will return the control chain toward its normal position far enough to permit the control chain to be moved along the channels 66 corresponding to the desired route, and so causing relay X^{1a} to become de-energized and the arm of signal S^{1a} to move to the "stop" position.

On account of relay T^1 being de-energized due to the presence of a train in section a—A, relay P^{S1} does not pick up when relay X^{1a} closes its contact 27 X^{1a} and the arm of signal S^{1a} , returning to its "stop" position, closes its contact 23. 75

In order to energize relay P^{S1} , the operator will therefore start the operation of time release J^{S1} . Contact 515^{JS1} which may be of the well-known clockwork type in the circuits for signals S^1 , shown in Fig. 16, will immediately open and, after the lapse of a measured interval of time, contact 25 of release J^{S1} will close, causing relay P^{S1} to become energized by a third pickup circuit passing from terminal x , through contacts 21 , 22 and 23 of signals S^{1c} , S^{1b} and S^{1a} , respectively, contact 25 of release J^{S1} , contact 27^{X1a} , and the winding of relay P^{S1} to terminal o . Relay P^{S1} , upon becoming energized, completes its stick circuit through its contact 551 , and hence the operator will now return release J^{S1} to its normal position. Relay P^{S1} being energized causes relay V^{S2} to again become energized. The operator can then energize relays m for the switches of any other route by moving the control chain along corresponding channels 66 in the control panel.

Assuming that the operator wishes to send the train, which has arrived in section a -A, over Route 2 from A to F, he will so move the control chain that contact members z^{S1} , z^{2n} , z^{3n} and z^{4r} are closed, causing relays k^1 , n^2 , n^3 and r^4 to be energized. Relays m^2 and m^3 will now again be energized in the normal direction by the closing of front contacts 590^{n2} and 599^{n3} , respectively. Relay m^4 will be energized in the reverse direction by its circuit passing from battery hh , through terminal 441 , winding of relay m^4 , and contacts 619^{u4} , 618^{QS6} , 617^{QS5} , 616^{V3e} , back contact 614^{n4} , and contact 615^{r4} back to battery hh , relays t^{2a} , and t^{3a} will now be energized as previously described, and relay t^{4a} will, when switch H^4 has been moved to its reverse position in response to the reverse energization of relay m^4 , be energized by its circuit passing from battery 13 , through reverse contact 14^{m4} , contact 558^{r4} , contacts 18 and 19 of relay h^4 , contact 20 of relay t^{4a} , and the winding of relay t^{4a} back to battery 13 .

Upon the energization of relay r^4 , a second circuit is completed for relay Y^1 passing from terminal x , through contacts 624^{Y6} , 625^{r4} , 633^{n3} , 642^{n2} , 635 of relay k^1 , and the winding of relay Y^1 to terminal o . Relay t^{4a} upon becoming energized then completes a second circuit for relay X^{1a} passing from terminal x , through contact 680 of relay X^{6a} , back contact 681^{Y6} , contacts 682^{t4a} , 683^{r4} , 671^{13a} , 670^{n3} , 669^{12a} , 668^{n2} , front contact 663^{Y1} , and the winding of relay X^{1a} to terminal o .

Relay Y^1 , upon becoming energized, again completes the circuit first traced for relay v , which then causes lamp w to again become lighted.

With relay X^{1a} energized, the arm of signal S^{1b} becomes operated to its proceed position by its circuit passing from terminal x , through contacts 514^{X1a} , 515^{JS1} , 516^{12a} , 525^{t4a} , 528 of signal S^{1a} , 529 of signal S^{1b} , and the mechanism of signal S^{1c} to terminal o . When the arm of signal S^{1c} leaves its stop position, approach locking relay P^{S1} becomes de-energized by the opening of contact 21 of signal S^{1c} . The arm of signal S^{1c} , upon leaving its stop position, opens, at its contact 93^{S1c} , the circuit for relay v , causing relay v to become de-energized, and this relay, in turn, causing lamp w to become extinguished.

The condition of the apparatus, as a train proceeds through the route from A to F, will be similar to that already described in connection with Route 1 from A to E. When the operator returns the control chain away from contact member z^{4r} , causing relay r^4 to become de-energized, switch H^4 will, however, remain in its reverse position.

When the operator later, in arranging another route, moves a control chain to close contact member z^{4n} , switch H^4 will be returned to its normal position due to the energization of relay n^4 by member z^{4n} , which causes relay m^4 to be energized in the normal direction.

Assuming now that all parts of the apparatus are again in the normal condition, and that the operator desires to arrange for a traffic movement over Route 3 from A to D, he will move the control chain from its position to the left of letter A to bridge contact members z^{S1} , z^{2r} and z^{3an} in the order named. Relays k^1 , r^2 and n^3 will therefore become energized. Relay m^2 will now be supplied with current of reverse polarity by its circuit passing from battery hh , through contact 591^{r2} , and back contact 590^{n2} , and thence through the circuit previously traced from contact 590^{n2} to terminal 441 for relay m^2 , and back to battery hh . Relay m^3 will be again energized in the normal direction by its circuit through contact 599^{n3} . With relays m^2 energized in the reverse direction, switches H^2 and H^{2a} will be operated to their reverse positions. Relay h^2 will then be energized in its reverse direction, and relay t^{2a} will then become energized.

Relay Y^1 will now be energized by a third circuit passing from terminal x , through contacts 620^{Y4} , 621^{n3} , 632^{r2} , 635 of relay k^1 , and the winding of relay Y^1 to terminal o . Relay t^{2a} , upon becoming energized, then completes, at its contact 665^{t2a} , a third circuit for relay X^{1a} passing from terminal x , through contact 672 of relay X^{4a} , back contact 673^{Y4} , contacts 674^{13a} , 675^{n3} , 665^{12a} , 664^{r2} , front contact 663^{Y1} , and the winding of relay X^{1a} to terminal o . The energization of relay Y^1 causes lamp w to be lighted as previously described. With relay t^{2a} energized, relay L^{S1} is energized by its circuit passing from terminal x , through contacts 40^{12a} , 41^{U6} , 42^{U7} , 46^{U2} , 47^{PS1} , and the winding of relay L^{S1} to terminal o . When relay X^{1a} becomes energized, signal S^{1b} becomes operated to its "proceed" position by its circuit passing from terminal x , through contacts 514^{X1a} , 515^{JS1} , 520^{12a} , 521^{13a} , 522^{LS1} , 523 of signal S^{1a} , and the mechanism of signal S^{1b} to terminal o . When the arm of signal S^{1b} leaves its "stop" position, relay P^{S1} becomes de-energized due to the opening of signal contact 22 . The arm of signal S^{1b} , upon leaving its stop position, opens its contact $94S1b$ which, by de-energizing relay v , causes lamp w to be extinguished.

I will next assume that all parts of the apparatus have again been returned to the normal condition, and that the operator wishes to send a train by Route 4 from A to E. He therefore moves the chain from letter A to bridge contact members z^{S1} , z^{2r} , z^{3r} and z^{4n} . Relays k^1 , r^2 , r^3 and n^4 therefore become energized. Switches H^2 , H^{2a} , H^{3a} and H^3 then move to their reverse positions, and relays t^{2a} and t^{3a} become energized as already described in connection with switches H^2 and H^{2a} . Relay Y^1 is now energized by a fourth circuit passing from terminal x , through contacts 622^{Y5} , 623^{n4} , 626^{r3} , 632^{r2} , 635 of relay k^1 , and the winding of relay Y^1 to terminal o . Relay X^{1a} then, upon the energization of relays t^{2a} and t^{3a} , becomes energized by a fourth circuit passing from terminal x , through contact 676 of relay X^{5a} , back contact 677^{Y5} , contacts 678^{14a} , 679^{n4} , 667^{t3a} , 666^{r3} , 665^{12a} , 664^{r2} , front contact 663^{Y1} , and the winding of relay X^{1a} to terminal o . The arm of signal S^{1c} is then operated to its "proceed" position by a circuit passing from terminal x , through contacts 75

5 **514^{x1a}, 515^{JS1}, 520^{t2a}, 524^{t3a}, 528** of signal S^{1a}, 529 of signal S^{1b}, and the mechanism of signal S^{1c} to terminal o. By the operation of the apparatus to clear signal S^{1c}, and the subsequent clearing of signal S^{1c}, lamp w becomes lighted and then extinguished as previously described.

10 Relay P^{S1} becomes de-energized upon the opening of contact 21 of signal S^{1c} when the arm of this signal leaves its "stop" position. Upon the de-energization of relay P^{S1}, relay V^{2ae} becomes de-energized due to the opening of contact 561^{PS1} while contact 562^{t2a} is open. Relay V^{2ae}, upon becoming de-energized, opens its contact 568^{V2ae}, thereby de-energizing relay V^{3ae}. Relay V^{3ae}, 15 upon becoming de-energized, opens its contact 573^{V3ae}, causing relay V^{3e} to be de-energized, contact 574^{t3a} being already open. With relay P^{S1} de-energized, relay m² is de-energized as already described, and with relay V^{3e} de-energized, relays 20 m³ and m⁴ are de-energized due to the opening of contacts 602^{V3e} and 616^{V3e}, respectively.

25 I will now assume that all parts of the apparatus are again in the normal condition, and that the operator desires to arrange for a traffic movement over Route 6 from B to D. He therefore moves, to the right, the chain which is shown in Fig. 1 to the left of letter B. By this means, he bridges contact members z^{2s2}, z¹ⁿ, z^{2an} and z^{3an}, causing relays k², n¹, n² and n³ to 30 be energized and relays m¹, m² and m³ to be energized by current of normal polarity. When switches H¹, H^{2a} and H^{3a} are in their normal position or have been operated to the normal position as controlled by relays m¹, m² and m³, relays i^{1a}, i^{2a} and i^{3a} will become energized after 35 relays h¹, h² and h³ have been energized in the normal direction as previously described for relay h⁴.

40 With relays n¹, n² and n³ energized, relay Y² is energized by its circuit passing from terminal x, through contacts 629^{Y4}, 621ⁿ³, 627ⁿ², 630ⁿ¹, 631 of relay k², and the winding of relay Y² to terminal o. Relay Y² then completes a third circuit for relay v, passing from terminal x, through 45 contact 93^{s2}, terminal e, front contact 96^{Y2}, and the winding of relay v to terminal o. Relay v then closes its contact 97, causing lamp w to be lighted. When relay Y² becomes energized, relay X^{2a} becomes energized by its circuit passing from terminal x, through contact 672 of relay X^{4a}, back contact 673^{Y4}, contacts 674^{i3a}, 675ⁿ³, 664^{t2a}, 669ⁿ², 659^{i1a}, 658ⁿ¹, front contact 657^{Y2}, and the winding of relay X^{2a} to terminal o. With relay X^{2a} energized, the arm of signal S² is operated to the "proceed" position by its circuit which is controlled by contact 513^{X2a}. The arm of signal S², when leaving its stop position, opens its contact 93^{s2} in the third circuit for relay v which then causes lamp w to become extinguished.

55 60 When the arm of signal S² leaves its "stop" position, stick locking relay Q^{S2} becomes de-energized by the opening of contact 28 of signal S². If a train now passes signal S² into section B-mm, relay T⁵ and, in turn, relay U⁵ will become de-energized, and relay I⁵ will become energized. If, now, the operator returns the control chain toward its normal position, relay Y² will become de-energized, completing a fourth circuit for relay v, passing from terminal x, 65 through contact 93^{s2}, terminal f, back contact 96^{Y2}, and the winding of relay v to terminal o. Lamp w will then become lighted. Relay X^{2a} will also be de-energized, by this movement of the control chain, causing the arm of signal S² to 70 return to its "stop" position. The arm of signal S²

75 nal S², upon leaving its proceed position, will open its contact 93^{s2}, de-energizing relay v, and so extinguishing lamp w. Relay Q^{S2} will be again energized by its pick-up circuit passing from terminal x, through contact 28 of signal S², contacts 29^{X2a}, and 30^{U5}, and the winding of relay Q^{S2} to terminal o.

If, on the other hand, before a train passes signal S², the operator should desire to arrange some other route which would conflict with the route from B to D, he will likewise first return the arm of signal S² to its "stop" position by returning the control chain toward its normal position. With the arm of signal S² again in its normal position, and with relay X^{2a} de-energized, 15 winding 31 of thermal relay N^{S2} will become energized by its circuit passing from terminal x, through contact 28 of signal S², contact 29^{X2a}, winding 31 of relay N^{S2}, and contact 34 of relay Q^{S2} to terminal o. Upon the lapse of a given period of time, relay N^{S2} will close its contact 32, causing relay Q^{S2} to become energized by a second pick-up circuit passing from terminal x, through contact 28 of signal S², contact 29^{X2a}, contact 32 of relay N^{S2}, and the winding of relay Q^{S2} to terminal o. With relay Q^{S2} now energized, the operator can arrange any other route which he may desire.

I have described, for a few typical traffic movements, the operation of the apparatus embodying my invention. From these descriptions and from the preceding general description, the operation of the apparatus for every other possible traffic movement will be readily understood upon reference to the drawings. 35

It will be clear that with apparatus embodying my invention, an operator in charge of the apparatus, in order to arrange any route and clear the signal for a given direction of traffic through the route, has only to move a corresponding control chain of Fig. 1 along the guides shown as channels 66 corresponding to the route. When the operator afterward desires to restore the control apparatus for the route to the normal condition, he will return the chain to its normal position. The arm of the signal for the route will at once return to its "stop" position, and, when all the track sections are again clear, the approach or stick locking relay for the route, and the route locking relays for the route will become energized. 50 The switches in the route will, however, remain in the positions to which they were previously operated for arranging the route.

It will also be clear that, due to interconnecting guides which correspond to the routes shown by the track layout in Fig. 8, when a control chain is in a position for arranging the switches for a given route, no other control chain can be moved into a position for arranging a route which would conflict with the given route. In this way, interlocking between routes is provided.

It follows that with apparatus embodying my invention, the control panel shown in Fig. 1 performs the functions of an interlocking machine and of the track model which is usually provided for the information of the operator.

The arrangement shown in Fig. 17 provides means comprising a single indicator, which may be an electric lamp as here shown, or may be of any other suitable type such, for example, as an electric bell, to indicate to the operator when the traffic governing devices associated in any given route fail to complete their response to a corresponding movement of a control chain.

As has been described, my invention provides 75

approach or stick locking, detector track circuit locking, route locking, and signal indication locking for all switches.

Although I have herein shown and described only one form of multiple control apparatus embodying my invention, it is understood that various changes and modifications may be made therein within the scope of the appended claims without departing from the spirit and scope of my invention.

Having thus described my invention, what I claim is:

1. In combination, a plurality of railway tracks inter-connected by means of a plurality of switches to form a plurality of routes, a signal adjacent each end of each route for governing traffic movements through the route in opposite directions, a diagram having a path corresponding to each of said routes, a switch contact member adjacent each said path for each switch of its route, a signal contact member adjacent each said path for each signal for the corresponding route, contact means movable in each direction along each said path for closing the contact members adjacent the path, means controlled by each said switch contact member for controlling an operation of its switch to the position in which the switch is included in the corresponding route, and means controlled by each said signal contact member for controlling its signal when a contact means is moved along the corresponding path in the direction corresponding to the direction of traffic movements controlled by said signal.
2. In combination, a plurality of railway tracks inter-connected by means of a plurality of switches to form a plurality of routes, a signal adjacent each end of each route for governing traffic movements through the route in opposite directions, a manually operable device for each switch for controlling an operation of the switch to its normal position, a second manually operable device for each switch for controlling an operation of the switch to its reverse position, a route relay for each route, a second route relay for each route, control means for each said first route relay controlled independently of the track switches by one of said manually operable devices for each switch in its route and by a back contact of the second route relay for the same route, control means for each said second route relay controlled independently of the track switches by one of said manually operable devices for each switch in its route and by a back contact of the first route relay for the same route, means controlled by each said first route relay and by each switch of its route for controlling the signal adjacent one end of its route, and means controlled by the second route relay for the same route and by each switch of said route for controlling the signal adjacent the opposite end of the route.
3. In combination, a railway track switch, a manually operable device, a second manually operable device, a polarized control relay for said switch energized in the normal or the reverse direction according as said first or said second device is operated, a polarized indication relay energized in the normal or the reverse direction according as said switch is in its normal or its reverse position, a normal indication means, a reverse indication means, means controlled by said first manually operable device and by normal contacts of said polarized indication and control relays for controlling said normal indication means, and means controlled by said second man-

ually operable device and by reverse contacts of said polarized indication and control relays for controlling said reverse indication means.

4. In combination, a plurality of partly inter-inclusive groups of railway traffic governing devices, a manually operable device for each of said groups, means controlled by each said manually operable device for controlling its group of said traffic governing devices, an indication means, and means controlled by each said manually operable device for controlling said indication means when the condition of its group of traffic governing devices does not correspond to the condition of said manually operable device.

5. Railway control apparatus comprising a panel having representations thereon of a plurality of railway tracks interconnected by a plurality of switches, a normal and a reverse contact element adjacent the representation of each of said switches, a plurality of movable contact elements manually controllable to move along said representations of railway tracks for making contact with said normal and reverse contact elements, a normal circuit for each switch including the associated normal contact element and one of said movable contact elements, a reverse circuit for each switch including the associated reverse contact element and one of said movable contact elements, and means controlled by each normal and reverse circuit for operating the associated switch to normal and reverse positions respectively.

6. Railway control apparatus comprising a panel having representations thereon of a plurality of railway tracks interconnected by a plurality of switches for forming a plurality of routes, a plurality of signals for governing traffic movements in opposite directions over said plurality of routes, a signal contact element adjacent each end of each of said track representations, a plurality of movable contact elements manually controllable to move along said track representations for making contact with said signal contact elements, a control circuit for each signal including a corresponding one of said signal contact elements and one of said movable contact elements for causing operation of the associated signal, and means controlled by each such signal control circuit for preventing operation of the opposing signal for the same route.

7. Railway control apparatus comprising a panel having representations thereon of a plurality of railway tracks interconnected by a plurality of switches for forming a plurality of routes, a plurality of signals for governing traffic movements in opposite directions over said plurality of routes, a signal control element adjacent each end of each of said track representations, a plurality of movable control elements manually controllable to move along said track representations for engaging said signal control elements, and means controlled by each signal control element through engagement with a movable control element for causing a corresponding signal to be cleared and for preventing the control of a second signal by the same movable control element.

8. Railway control apparatus comprising a panel having representations thereon of a plurality of railway traffic governing devices, a control element mounted on said panel for each of said traffic governing devices, two movable elements each associated with a particular traffic governing device, each being manually controllable to move along said panel for engaging each

- of said control elements, and interlocked means controlled by each said movable element through engagement with certain of said control elements including the one for the traffic governing device 5 associated with such movable element for causing the operation of such device, said means including means for preventing the operation of the traffic governing device associated with the other movable element.
10. In combination, a railway track switch, a manually operable device, a second manually operable device, a polarized control relay for said switch controlled by said manually operable devices to be energized in the normal or the reverse direction according as said first or said second device is operated, a polarized indication relay energized in the normal or the reverse direction according as said switch is in its normal or its reverse position, a normal indication relay, a reverse indication relay, a circuit controlled by said first manually operable device and by normal contacts of said polarized indication and control relays for energizing said normal indication relay, a second circuit controlled by said second manually operable device and by reverse contacts of said polarized indication and control relays for energizing said reverse indication relay, and indication means controlled by said normal and reverse indication relays.
15. 10. In combination, a railway track switch, a normal switch relay, a reverse switch relay, a manually controlled circuit for each of said switch relays for energizing the corresponding switch relay, a normal and a reverse operating circuit controlled by said normal and reverse switch relays for causing said switch to be operated to its normal and reverse positions respectively, a polarized indication relay energized in the normal or the reverse direction according as said switch 30 is in its normal or its reverse position, a normal indication relay, a reverse indication relay, a circuit including a front contact of said normal switch relay and a normal contact of said polarized indication relay for energized said normal indication relay, a second circuit including a front contact of said reverse switch relay and a reverse contact of said polarized indication relay for energizing said reverse indication relay, and indication means controlled by said normal and 35 reverse indication relays.
11. In combination, a plurality of railway tracks interconnected by switches to form a plurality of partly interinclusive railway routes, a signal for each direction of traffic movements over each of said routes, a normal and a reverse manual control contact for each of said switches, means controlled by the normal and reverse manual control contacts for each switch for operating the switch to normal and reverse positions respectively, a manually controllable signal control contact for each signal, a route relay for each signal, one or more circuits for controlling each route relay each of which circuits is controlled by the signal control contact for the corresponding signal and by the normal or the reverse manual control contact for each switch in a corresponding route governed by the signal as well as controlled by a back contact of the route relay for the opposing signal for the same route, a signal 45 control relay for each signal, one or more circuits for controlling each signal control relay each of which circuits is controlled by a front contact of the route relay for the signal and by the normal or the reverse manual control contact for each switch in a corresponding route governed by the signal as well as by the normal or the reverse control contact for each switch in the same route, and means controlled by each signal control relay for clearing the corresponding signal.
12. In combination, a plurality of railway tracks interconnected by switches to form a plurality of partly interinclusive railway routes, a signal for each direction of traffic movements over each of said routes, a normal and a reverse manual control contact for each of said switches, means controlled by the normal and reverse manual control contacts for each switch for operating the switch to normal and reverse positions respectively, a manually controllable signal control contact for each signal, a route relay for each signal, one or more circuits for controlling each route relay each of which circuits is controlled by the signal control contact for the corresponding signal and by the normal or the reverse manual control contact for each switch in a corresponding route governed by the signal as well as by the normal or the reverse control contact for each switch in the same route, and means controlled by each signal control relay for clearing the corresponding signal.
13. In combination, a plurality of railway tracks interconnected by switches to form a plurality of partly interinclusive railway routes, a signal for each direction of traffic movements over each of said routes, a normal and a reverse manual control contact for each of said switches, means controlled by the normal and reverse manual control contacts for each switch for operating the switch to normal and reverse positions respectively, a manually controllable signal control contact for each signal, a route relay for each signal, one or more circuits for controlling each route relay each of which circuits is controlled by a front contact of the route relay for the signal and by the normal or the reverse manual control contact for each switch in a corresponding route governed by the signal as well as by the normal or the reverse control contact for each switch in the same route, and means controlled by each signal control relay for clearing the corresponding signal.
14. In combination, a plurality of railway tracks interconnected by switches to form a plurality of partly interinclusive railway routes, a signal for each direction of traffic movements over each of said routes, a normal and a reverse manual control contact for each of said switches, means controlled by the normal and reverse manual control contacts for each switch for operating the switch to normal and reverse positions respectively, a manually controllable signal control contact for each signal, a route relay for each signal, one or more circuits for controlling each route relay each of which circuits is controlled by the signal control contact for the corresponding signal and by the normal or the reverse manual control contact for each switch in a corresponding route governed by the signal as well as controlled by a back contact of the route relay for the opposing signal for the same route, a signal control relay for each signal, one or more circuits for controlling each signal control relay each of which circuits is controlled by a front contact of the route relay for the signal and by the normal or the reverse manual control contact for each switch in a corresponding route governed by the signal as well as by the normal or the reverse control contact for each switch in the same route, and means controlled by each signal control relay for clearing the corresponding signal.
15. In combination, a plurality of railway tracks interconnected by switches to form a plurality of partly interinclusive railway routes, a signal for each direction of traffic movements over each of said routes, a normal and a reverse manual control contact for each of said switches, means controlled by the normal and reverse manual control contacts for each switch for operating the switch to normal and reverse positions respectively, a manually controllable signal control contact for each signal, a route relay for each signal, one or more circuits for controlling each route relay each of which circuits is controlled by the signal control contact for the corresponding signal and by the normal or the reverse manual control contact for each switch in a corresponding route governed by the signal as well as controlled by a back contact of the route relay for the opposing signal for the same route, a signal control relay for each signal, one or more circuits for controlling each signal control relay each of which circuits is controlled by a front contact of the route relay for the signal and by the normal or the reverse manual control contact for each switch in a corresponding route governed by the signal as well as by the normal or the reverse control contact for each switch in the same route, and means controlled by each signal control relay for clearing the corresponding signal.

cluding front contacts of the normal or the reverse control relay for each switch in the corresponding route, and contacts controlled by the signal control contact for said signal, and a signal relay controlled by each route relay for clearing the corresponding signal.

15. In combination, a plurality of railway tracks inter-connected by means of a plurality of switches to form a plurality of routes, a signal adjacent each end of each route for governing traffic movements through the route in opposite directions, a manually controllable relay for each position of each switch for controlling an operation of the switch to its normal or reverse position respectively, to select a route, a route relay for each signal, a control circuit for each route relay independent of the track switches but including contacts of one of said manually controllable relays for each switch of the selected route and a back contact of the route relay for the signal adjacent the opposite end of the selected route, and means controlled by each route relay and by each switch of the selected route for controlling the corresponding signal.
20. In combination, a plurality of railway tracks inter-connected by means of a plurality of switches to form a plurality of routes, a signal adjacent each end of each route for governing traffic movements through the route in opposite directions, manually controllable means for each switch for controlling an operation of the switch to its normal or reverse position, respectively, to select a route, a route relay for each signal, control means for each route relay controlled independently of the track switch by the manually controllable means for each switch of the selected route and by a back contact of the route relay

for the signal adjacent the opposite end of the selected route, and means controlled by each route relay and by each switch of the selected route for controlling the corresponding signal.

17. In combination with a track switch having two positions, two control relays, including one for each position of the switch, two indication relays, including one for each position of the switch, means effective when a control relay becomes energized for moving the switch to a corresponding position, means effective only when a control relay is energized and the switch occupies said corresponding position for energizing the corresponding indication relay, and means controlled by track conditions and by said indication relays for governing traffic over the switch.

18. Railway control apparatus comprising a panel having representations thereon of a plurality of track switches and of two opposing signals for governing the movement of traffic in opposite directions over the switches, a control element mounted on said panel for each switch and signal, a movable element for each signal manually controllable to move along said panel to engage said control elements, and interlocked means controlled by each movable element through engagement with the control elements for each of said switches and for the corresponding signal for clearing such signal, and means controlled by said interlocked means for preventing the clearing of the opposing signal in response to the engagement of a movable element with the control element for said opposing signal.

HOWARD A. THOMPSON.
